FREDERICK G. ZINSSER, OF HASTINGS-UPON-HUDSON, NEW YORK.

FEEDING MECHANISM FOR BOTTLE-STOPPERS.

1,094,163.

Specification of Letters Patent. Patented Apr. 21, 1914.

Application filed February 10, 1912. Serial No. 676,897.

To all whom it may concern:

Be it known that we, TOIMI A. NISSINEN and CHARLES HARTWIG, subjects, respectively, of the Czar of Russia and the Emperor of Germany, said NISSINEN being a legal resident of Helsingfors, Finland, Russia, but now residing at the city of New York, borough of Bronx, and said HARTWIG residing at the city of New York, borough 10 of Manhattan, State of New York, have invented certain new and useful Improvements in Feeding Mechanism for Bottle-Stoppers and the like, of which the following is a full, clear, and exact description.

15 This invention relates to feeding mechanisms for caps and the like, and is particularly adapted for use in connection with bottle capping machinery.

One of the objects of our invention when 20 the same is applied to bottle capping machines, is to positively feed the caps one at a time to the capping throat or device, or to the vicinity thereof.

Another object of our invention is to 25 provide means whereby all possibility of interference between successive caps, when one of these is being applied to a bottle, is eliminated.

Yet another object of our invention is to 30 do away with the possible handling of the caps by the, in many instances, unclean hands of the operatives.

Still another object of our invention is to 35 provide means in connection with the feed chute, whereby said chute may not become choked or clogged, owing to the pressure of an excessive number of stoppers in the same.

These and other objects of our invention 40 will be hereinafter referred to and the novel elements and combinations of elements whereby the same may be attained will be more particularly set forth in the claims appended hereto.

In the drawings which form a part hereof 45 and in which like reference characters designate like parts throughout the several views, we have exemplified a preferred embodiment of our invention; but it will be understood that many modifications and changes 50 may be made therein without departing from

the spirit of the invention, and we hence desire to be limited only by the scope of the appended claims.

Referring to the drawings: Figure 1 is a side elevation of a portion of a capping machine with our feeding mechanism applied thereto. Fig. 2 is a plan of the same. Fig. 3 is a section of the feeding mechanism in combination with a capping head, the section being taken on line III—III of Fig. 2. Fig. 4 is a detail section of the same taken on line IV—IV of Fig. 3. Fig. 5 is a supplemental detail section of a portion of the device shown in Fig. 3, certain of the parts being, however, in different positions. Fig. 6 65 is a detail of the cap separating construction.

The apparatus herein more particularly shown is intended to be usable in connection with a number of different types of bottle 70 capping machines which are now commonly in use. Where changes are necessary before the feeding mechanism can be applied to such a machine to which it is otherwise not perfectly adapted, such changes will, in 75 most instances, involve merely the use of ordinary mechanical skill.

In Fig. 1 we have shown a portion of the standard 1 of a typical capping machine, a lug 2 projecting from one side of this standard, into which is threaded the stem 3 of a bottle supporting table 4. This table may be provided, of course, with the usual resilient pad 5. Reciprocably mounted in the standard 1 is the usual upright shaft 6 which 80 carries a capping head 7. In this particular instance the capping head is adapted for use in connection with a novel stopper which we have devised, but which will not be herein described, since it forms no part of the 85 present invention. The head, broadly designated 7, comprises a casting 8, or the like, preferably of brass, which has laterally projecting therefrom an extension or arm 9, the outer extremity of which is enlarged as at 95 10, in the usual fashion, to adapt it for the reception of the extremity of the shaft 6. The part 10 is clamped upon this upper extremity of the shaft in the usual manner by means of a nut 11, or the like. The head is 100

preferably hollow and is adapted to receive into the lower end thereof, a capping throat 12, of any suitable type. This throat is held in place by means of a guide block 13, which 5 is recessed upon the lower side thereof, as at 14, to form a guide for the head of a bottle, when said block, together of course with the head, is being driven downwardly toward the same; or vice versa. The upper 10 side of the guide block is preferably recessed as at 15 for the reception of the lower portion of the throat 12 and the block is further provided with a laterally opening passage 16, through which the caps 17 may 15 be delivered to the cap supporting ledge 18 disposed substantially intermediate the recesses 14 and 15. In so far as the provision of blocks of this type, adapted to retain a capping throat in position and provided 20 with a feed passage, is concerned, there is nothing particularly novel in what has just been described, but it has been customary to either rotate this entire block for the purpose of securing the same by a threaded connection 25 to the bottom of a capping head, or to provide some form of nut in connection therewith, adapted for this purpose. Where the nut has been separately provided, it has to the best of our knowledge always been 30 more or less loosely connected to the guide block, so that in use it is apt to become separated therefrom, as by being unscrewed, and thereby is frequently lost or mislaid. Furthermore, the operatives for mechanisms 35 of this character are not always high class mechanics and are apt therefore to inadvertently injure portions of the mechanism to which they may gain access, if nothing worse; burring up threads, and the like. 40 It is disadvantageous to form the nut and the guide block in one piece, in the manner previously referred to, owing to the fact that the cap feed passage in the block must be alined with the chute or the like through 45 which the caps are delivered. We have overcome these difficulties and objectionable characteristics by providing a freely revolvable nut in connection with the guide block, which, moreover, is inseparable therefrom. 50 Referring more particularly to Fig. 3, the nut 19 therein shown is adapted for threaded engagement with the lower extremity 20 of the casing or casting 8. It is further interiorly grooved as at 21 in the lower portion 55 thereof; groove 21 being disposed in the annular wall of a recess into which the upper extremity of the guide block 13 extends. The exterior wall of this guide block is correspondingly recessed or grooved as at 60 22, the grooves 21 and 22 preferably exactly coinciding with each other when the parts are in assembled relationship. The groove 22 is made of sufficient depth to receive a resilient expansion ring 23, so that the up-

per extremity of the block with the ring in 65 place therein may be pushed up into the ring 19, and when the grooves come into coincidence with each other the ring 23 will snap outwardly into the groove 21, substantially half of the ring being then in the last mentioned groove, and half in the groove 22. This construction renders it substantially impossible to separate the members 19 and 13 when they have once been assembled, while at the same time the ring or nut 19 70 is perfectly free to revolve with respect to the guide block 13. This permits the block to be drawn up firmly against the lower end of the casing 8, with the passage 16 so directed as to be in alinement with the channel 75 24, which extends through the channel frame 25. This latter depends from a slide box, 26, being secured thereto in any suitable manner, as by means of screws 27. The channel may be covered by an arcuate plate 80 28, which latter preferably has apertures 29 therein to afford access to the interior of the channel and to permit inspection of the same without removal of said cover plate. The member 26 is secured by means of a bolt 85 28' or the like to a bracket 30, which latter is mounted upon the upper extremity of the shaft 6; preferably immediately below the part 10 of the head. Bracket 30 is so constructed that it may readily be removed 90 from shaft 6 when desired; and to this end is held in position thereon by means of a cap 31 and bolts 32, or the like. The slide-box 95 26 is recessed substantially as shown in Fig. 3 for the reception of a slide 32; and further to form a passage-way through which a cap urged laterally by means of this slide, in the manner hereinafter described, may pass down into the channel 24. To afford access to this portion of the mechanism, the 100 slide-box 26 may be provided with a separable cover plate 33, which may be secured to it in any suitable manner, as by means of screws 34. Upwardly projecting from the cover plate 33 is a tubular structure 35, the 105 hollow interior of which is in communication with the slide-way in the cross-member 26. The cylindrical aperture in the interior of the part 35 is preferably countersunk as at 36 for the reception of the extremity of 110 a tube 37. This tube may be of paper, sheet metal, or any other suitable material, and is adapted to contain the stoppers 17 which are delivered to the capping throat. In practice we contemplate providing a tube of sufficient 115 length to contain, let us say, one gross of stoppers. The tubular part 36 is provided with a projection 38 upon one side thereof, from which project ears 39, and a bell-lever 40 is pivotally mounted between these ears, 120 as upon a pin 41. The longer arm of this lever extends downwardly toward and into engagement with the rear extremity of the 125

slide 32, which in this instance is recessed for the reception of the rounded nose or end 42 which constitutes the lower extremity of this arm. The short arm of the bell-lever 40 is laterally directed toward the spindle 43 which projects upwardly from the plunger 44 within the capping head; said short arm preferably having the extremity 45 thereof somewhat hooked to adapt it for engagement with the flange 46 of a nut 47, which is adjustably mounted upon the upper extremity of the spindle 43. The plunger 44 may be provided with a collar 48 which is preferably integral therewith, whereby its downward movement may be limited; collar 48 engaging an annular rib or ledge 49 within the casing 1 when in its downward position. Of course, the weight of the plunger will normally tend to hold it thus; but we prefer to provide a spring 50, preferably helical in character, around the stem or spindle 43, the lower extremity of this spring engaging the collar 48 and the upper extremity bearing against a plug 51, which is screwed into the upper end of the head. The plunger 44 is hence guided in its movements by the rib 49 and the plug 51 through which the stem 43 projects. We are aware that it is old to provide springs in the interior of a capping head for the purpose of normally holding the plunger therein in its downmost or outermost position; but the spring 50 has an additional function, in that it co-acts with a portion of the stopper feed mechanism in this embodiment of our invention. The slide 32 is preferably made of substantially the same thickness as the cap 17, and in the mechanism shown the upper portion of this slide is flattened to form a table or support for the cap 17 immediately thereabove, when the parts are disposed as shown in Fig. 3. It will be noted also that the cap 17, which bears against slide 32, is inverted; and it is our intention that all of the caps within the tube 37 shall be directed the same way, so that, in at least the herein more particularly described mechanism, the cap flanges shall always be uppermost. Thus as cap after cap is removed from the bottom of the column of caps through the instrumentality of the slide 32 in the manner presently to be described, the caps will normally always present themselves to this slide with their flanges uppermost. The slide 32 is maintained in its column supporting position, *i. e.* that shown in Fig. 3, by the action of the spring 50 previously referred to; since the nut 47 is initially screwed downwardly when the plunger is in its lowermost position until the longer arm of the lever 40 has been swung fully to the right, as viewed in said figure, thereby pushing the slide beneath the cavity in the member 36. The slide 32, how-

ever, is pressed toward its left hand position through the instrumentality of a spring 52. This spring may be a bowed flat spring, as shown, having a tendency to straighten itself out, and by reason of this action, tending to elevate the short arm of the bell-lever. 70

In the lower portion of the structure shown in Fig. 3, is a finger 53, which is pivoted upon a short shaft or spindle 54, the extremity of the finger being movable through a slot 55 in the under side of the lower extremity of the channel 25. The function of this finger is as follows: It is evident that if but a single stopper be positioned in the lower end of the channel 24, such stopper would have practically no tendency to continue its movement around laterally into a position where it could properly be engaged by the head of a bottle. It is, therefore, desirable that a plurality of stoppers be disposed in said channel, in order that gravity may exert sufficient lateral effort to properly position the foremost cap in the manner above described. This provision of a channel for stoppers in connection with a guide-block or the like, is, as we have previously indicated, old. Considerable difficulty, however, has been encountered in practice owing to the fact that a sufficient clearance in the channel and stopper-passage must be provided to allow the stoppers or caps to move freely through said passages or channels. As the metal of which the stopper is formed is usually quite light, there is a strong tendency for the flanges of adjacent stoppers to overlap, and if, for example, the cap behind that shown directly beneath the plunger 44 should so overlap said last mentioned cap, one or possibly both of these caps would be deformed when the first cap was applied to a bottle. 105 The finger 53 provides a means for positively withdrawing the second cap out of contact with first, after the first has been properly positioned. This action will be hereinafter more fully discussed in connection with the operation of the mechanism as a whole. The spindle 54 upon which said finger is mounted, is adapted to be rotated by means of a pinion 56, which is disposed upon the farther extremity of said spindle, 110 as viewed in Fig. 3, and upon the near extremity of the same, as viewed in Fig. 6. This pinion is in engagement with a rack 57, the lower extremity of which is movable through a guide bracket 58 (see Fig. 6). 120 The rack 57 is formed preferably by notching the lower extremity of a rod 59 which extends upwardly through an aperture in a guide plate 60, secured to the under side of the slide-box 26. Adjacent the upper extremity of this rod, and secured thereon in any suitable manner, is a collar 61, against which bears a coil spring 62, the lower ex-

tremity of which presses against the plate 60. The rod 59 is hence normally held in its uppermost position through the action of this spring 62. Adjacent the lower extremity of the rod, however, and immediately above the rack 57, is a finger piece 63 which is rigidly secured to said rod in any suitable manner, and the extremity of this finger piece is intended to be positioned directly beneath one of the guiding ears 64—64', which are usually provided upon the upper extremity of the standard 1. These ears in known constructions receive a wing 65, which is upon one side of the head, and thereby prevent the latter from inadvertently rotating out of alinement with the table 4. We have utilized one of these ears in the present construction, causing it to act as a portion of the stopper feed mechanism; the under side of ear 64 being adapted for engagement with the finger piece 63 when the latter has been carried upwardly by the head to its uppermost position. It is obvious, however, of course that any suitable finger engaging means may be utilized in lieu of the ear 64, and we do not wish to be limited thereto, it being merely incorporated as a part of the feed mechanism in a preferred construction.

30 The operation of our novel mechanism is as follows: Assuming that the shaft 6 is in its uppermost position and that thereby the head 7, bracket 30 and attached parts are correspondingly positioned. In such case the finger piece 63 upon the rod 59 will have been urged upwardly into engagement with the lug 64, while in fact the head has moved slightly farther upwardly. This action will compress the spring 62 and the rod 59 will 35 be depressed with respect to the head. The spindle 54 will, through the action of the pinion 56 and rack 57, be rotated counter-clockwise as viewed in Fig. 3, which will swing the finger 53 around through the slot 40 55 in the channel 25, so that it no longer projects up into the channel. This permits the stoppers to freely descend through channel 25 and the foremost of them will be urged laterally until it is directly disposed 45 beneath plunger 44. If now the table 4 has been properly adjusted, in the usual manner, and a bottle has been placed thereon preparatory to capping the same, and the head 7 is caused to descend in a known manner, the first action of the feed mechanism 50 proper will be a relative movement between the rod 59 and the descending head; this action being due to the spring 62. This results in an upward rotation of the finger 53, the extremity thereof swinging around into the channel, and thereby engaging the stopper behind that directly beneath the plunger. The continued movement of the finger 53 positively pulls this stopper together

with the limited number of the same there- 65 behind which are disposed in the channel, backwardly and upwardly away from the cap which is to be applied to the bottle; and thereafter the spring 62 will hold the caps in channel 24 against downward move- 70 ment until the rod 59 has again been depressed by the engagement of the finger piece 63 and lug 64, which latter action will not occur until the head is substantially 75 again in its uppermost position. By no pos- sibility therefore at any time can a second cap interfere with the first when the latter is being applied to its bottle. Considering 80 now that the head of the bottle has entered the conical guide-way 14 in the usual manner and that the cap 17 thereabove has been positioned firmly upon the bottle head through the instrumentality of the plunger 44. Thereafter the continued downward movement of the head will force the cap 85 into the throat 12 in the usual manner, and the cap flange will be wiped or otherwise moved downwardly and around into en- 90 gagement with the bead at the head of the bottle. While this operation is taking place, considerable relative movement is occurring 95 between the plunger 44 and its casing 8. As a result, relative movement also occurs between the nut 47 and the pivot pin 41 of the bell-lever, the nut 47, in this particu- 100 lar form of the device, being practically sta- tionary, while said pivot pin continues to descend. The result of this movement is to enable the spring 52 to rotate the bell-lever 40 about its pivotal axis, and swing the ex- 105 tremity 42 of its longer arm into the position in which it is shown in Fig. 5. The column of caps in the tube 37 and member 35 de- 110 scend under the action of gravity a distance substantially equivalent to the thickness of one cap, the lowermost cap 17 falling di- 115 rectly in front of the slide 32. When the shaft 6 starts its upward movement the plunger 44 aids in ejecting the bottle from the capping throat in the usual manner, and this relative downward movement of the plunger with respect to the pivotal pin 41, above referred to, again brings the flange 46 of the nut 47 into engagement with the hook 45 of bell-lever 40. Thereafter the 120 continued relative downward movement of the plunger with respect to said pivotal pin compresses spring 52 and swings the slide 32 back into its position beneath the column of caps, sweeping the cap which has pre- 125 viously fallen in front of the slide laterally with respect to said column, the cap falling down around and into the channel 24. It will be observed that this substantially effects a reversal of the cap, for whereas in the tube the shive holding face or side of each of the caps was uppermost, in the lower portion of the channel the shives and

their surrounding flanges are now downwardly faced to adapt them for engagement with the bottle head. Thus every time that a stopper or cap is removed from the chute 5 by being applied to a bottle, a new cap is introduced into the top of the chute, and, hence, but few stoppers need be disposed at any one time within the channel, the number preferably being only such as to insure 10 a proper feed into the guide block. As a result of this arrangement there is no tendency for the caps to jam in the guide-way; as is the case where an extended column of caps is disposed therein. If by any chance 15 one or more caps in a tube 37 should be reversed or improperly positioned so that its flange is lowermost, such stopper or cap will not be delivered to the channel 24, because two short guard pins 66, or the like, are 20 placed one upon either side of the sloping entrance to the channel, which pins will permit a cap, if properly positioned, to pass therebetween, the flange of the cap passing over the pins. Said pins will, however, effectually stop any cap otherwise disposed. 25 Immediately above the upper extremity of the channel 24 is an aperture 67, preferably in the cover plate 33 of the cross-member 26, whereby stoppers or caps may be separately 30 introduced into said channel, if desired. Here again, the shape of the aperture 67 is such that the stoppers may only be fed in when properly positioned.

In order to be able to promptly remove 35 any cap which has been delivered through the tubular member 36 improperly faced or directed, we provide openings 68 upon either side of the member 26, which open into the slide-way therein so that any suitable flat 40 implement may be inserted from one side of the device through one of said holes or apertures 68, whereby the improperly faced, or possibly deformed, cap may be ejected through the other and corresponding opening 68. The fact that the slide 32 yieldingly urges the stoppers toward the pathway 45 is of considerable importance, in that it prevents the mutilation or deformation of the caps when they chance to be improperly faced or directed in the manner above described; spring 52 of course being merely strong enough to displace a cap and not to deform the same. We preferably provide a slot 69 upon one side of the tubular member 50 36, so that when the tube 37 is inserted thereinto the stoppers may be held by the finger of the operator against inadvertent reversal, until the bottom-most stoppers have been allowed to enter well into the said 55 tubular member; the short distance through which they may then fall, and especially when a column of stoppers is therebehind, not affording an opportunity to said lowermost stoppers to rotate or flip over.

It will thus be seen that we have provided 65 a mechanism which is dependable in its action and in which certain existing parts of known machines are given new functions. The provision of stoppers in tubes does away with the costly rotary feed hoppers 70 and like devices, and is further very much more sanitary, there being practically no necessity for the fingers of the operator to come into contact with the cork shives of the steppers, at any time. We regard the 75 provision of means, e. g., the finger 53, for withdrawing the succeeding stopper out of engagement with that about to be applied to a bottle as of particularly great importance, while the desirability of maintaining 80 but a very short column of stoppers placed edge to edge should not be overlooked. The initial cylindraceous arrangement of the caps in the tube, or the like, from which they are fed to the chute is also advantageous in 85 that thereby the size of a column containing, let us say, a gross of caps is not unduly extended as would be the case if such caps were disposed edge to edge rather than face to face, so to speak. 90

Having described our invention, we claim:

1. A feeding and capping mechanism for bottle stoppers and the like which comprises a capping head having cap applying parts therein, a member stationary with respect to 95 said head and containing a channel for conveying caps to a definite position with respect to said cap applying parts, and means for moving a succeeding cap along said channel and away from a cap which has 100 been operatively positioned with respect to said cap applying parts, whereby to prevent possible mutilation of one of said caps when the operatively positioned cap is applied to a receptacle. 105

2. A feeding and capping mechanism for bottle stoppers and the like which comprises a capping head having cap applying parts therein, a member stationary with respect to 110 said head and containing a channel for conveying caps to a definite position with respect to said cap applying parts, and means for moving a succeeding cap along said channel and away from a cap which has been operatively positioned with respect to 115 said cap applying parts, said means including a movable part adapted for engagement with said succeeding cap.

3. A feeding and capping mechanism for bottle stoppers and the like which comprises 120 a capping head having cap applying parts therein, a member stationary with respect to said head and containing a channel for conveying caps to a definite position with respect to said cap applying parts, and 125 with respect to said cap applying parts, and means for moving a succeeding cap along said channel and away from a cap which

has been operatively positioned with respect to said cap applying parts, said means including a movable finger adapted for engagement with said succeeding cap and 5 mechanism for moving said finger.

4. In a bottle capping machine, the combination with a capping head, of a chute fixed with respect to said head and adapted to feed caps thereto, and a device adapted 10 to engage a cap in the chute and move it

away from the capping head while another cap is being applied to a bottle.

In witness whereof, we subscribe our signatures, in the presence of two witnesses.

TOIMI A. NISSINEN.
CHARLES HARTWIG.
